UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-DOOR-LOCKING MEANS.

1,244,779.

Specification of Letters Patent. Patented Oct. 30, 1917.

Original application filed May 27, 1914, Serial No. 841,280, which resulted in Patent No. 1,184,024, dated May 23, 1916. Divided and this application filed September 28, 1915, Serial No. 53,028.

To all whom it may concern:

Be it known that I, JOHN M. ROHLFING, residing at St. Louis, Missouri, and being a citizen of the United States, have invented certain new and useful Improvements in Car-Door-Locking Means, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

Figure 1 is a horizontal section of a hopper portion of a dump car, showing the door operating and locking mechanism in plan.

Fig. 2 is a vertical section through the same portion of the car and is taken centrally and longitudinally thereof.

Fig. 3 is a transverse section through the car and is taken on line 3—3 of Fig. 1.

Fig. 4 is a transverse section through the center sills and portions of the doors of the car, and illustrates one of the door-locking devices, being taken on line 4—4 of Fig. 1; and

Fig. 5 is a similar transverse section but is taken on line 5—5 of Fig. 1 and shows the door raising chains passing over one of their roller supports and extending to attachment devices on the doors.

This invention relates to the opening and closing of the doors of a dump car and to means for locking the doors when in closed position and this application is a division of my application on car door operating mechanism, Serial No. 841,280, filed May 27, 1914, which resulted in Patent 1,184,024, dated May 23, 1916.

Provision is also made for unlocking the doors at such times as it is desired to discharge lading, and the arrangements are such that the weight of the load carried by the car will operate the doors to move them to their open positions.

Mechanism is included by the use of which the doors may readily be returned to their closed positions after the lading has been

discharged; and, as the doors have been relieved of the weight formerly sustained by them, the door-closing parts of the mechanism may be of comparatively light construction.

Insurance against an accidental release of the doors is given by an inter-locking of certain parts of the mechanism, and this interlocking relationship may be interrupted at will, whereupon the door opening, closing and locking operations may take place in proper order.

The disposition of the elements of the door-operating and locking mechanism permits a large portion of it to occupy restricted space, like that between the center sills of a car, and in this location the design enables different portions of said mechanism to act at different times, one portion passing through the other in such manner that both are unobtrusive to each other in any of their positions.

Despite the disposition of much of the door-operating and locking mechanism centrally and longitudinally of the car, parts of it extend transversely thereof and said mechanism is operable from the car sides, which makes it very convenient and safe for the workmen engaged in manipulating it.

In discharging a load and reclosing and locking the doors, the workmen usually endeavor to accomplish their task quickly and exercise little care, and, therefore, the mechanism has been made to require but simple action to operate it and is free from the necessity of careful adjustment to tightly close and lock the doors.

Other advantages appearing hereinafter are to be considered as parts of this invention.

Referring to the drawings, 1 indicates a chain spool shaft, which passes through the bearings 2 and 3 secured to the side walls, and bearings 4 and 5 positioned upon and affixed to the center sills, of a car. Hand wheels 6 are secured to opposite ends of shaft 1 to permit it to be revolved to effect a winding up of the chains, as hereinafter more fully set forth.

Mounted on the shaft 1, is a chain spool 7, located between bearings 4 and 5, and ratchet wheel 8 outside of bearing 5. The

cylindrical hub of the said ratchet wheel passes through and is directly and revolvably mounted in bearing 5, and one end of spool 7 is mounted in like manner in bearing 4, both said hub and said spool-end serving as bushings for shaft 1.

As spool shaft 1 is preferably of rectangular cross-section, and passes through similar shaped axial holes in said ratchet wheel and spool, a rotary movement of hand wheel 6 causes a like motion of said ratchet wheel 8 and spool 7. The spool shaft 1, however, is not necessarily restricted to the section described, and the hand and ratchet wheels and the chain spool may be attached by keys, pins, or any convenient means.

Parallel to spool shaft 1, but shown as occupying a lower position, is a coöperating shaft 9, also, by preference, having a rectangular cross-section. On each of its ends, outside of the car side walls, is secured an operating handle 10, weighted at its outer end.

Coöperating shaft 9 also receives its support from bearings 2, 3, 4 and 5, though, like spool shaft 1 it does not directly contact therewith. A locking arm 11 and a ratchet pawl 12, having hubs, axially perforated and so as to conform to the section of coöperating shaft 9, are mounted on said shaft, the pawl 12 being alined with and adapted to engage ratchet wheel 8 on shaft 1 and the locking arm 11 being located outside of the center sill-supported bearing 4. The hub of locking arm 11 is cylindrical and is revolvably supported in said bearing 4, and a bushing 13, surrounding coöperating shaft 9, turns in bearing 5 and supports the said shaft at this point.

40 The center sill construction of the car comprises a pair of spaced apart longitudinal members, here conveniently shown as channels 14, having their top and bottom flanges inturned. Below the top flanges, and inwardly from shaft 9, is a sheave wheel 15, centrally disposed between the center sills 14, and supported by suitable bearings 16 attached to the inner faces of the sills.

50 Progressively spaced from sheave wheel 15, and at substantially uniform distances, are rolls 17, also located between the center sills 14, but occupying a lower position than sheave 15. Rolls 17 are comparatively long, being shown as nearly equal in length to the distance between the center sills 14, to the inner faces of which bearings 18 for said rolls are secured.

Securely attached at one end to a proper point on chain spool 7, is a two-part chain 19, hereinafter referred to as the central chain. The two central chain parts are connected by a small perforated triangular-shaped connecting plate 20, and to the

free end of the chain another plate 20^a is secured.

To outwardly projecting corners of the chain connection plate 20, intermediate the length of the central chain 19, are attached forward side chains 21, one on each side of said central chain 19. Rear side chains 22 are attached to corresponding corners of a second connection plate 20^a at the rear free end of the central chain 19, and extend to and over the rear roll 17, the forward side chains 21 extending rearwardly from their plate 20 and extending to and over the forward roll 17.

Each end of each side chain 21 and each side chain 22, after extending over its respective roll 17, passes through an aperture in a door casting 23, secured to one of the doors 25, and is attached to an adjustable eyebolt 24 carried by said casting.

The chains run underneath sheave wheel 15, which keeps central chain 19 running centrally, and over rolls 17. The latter permit side play of side chains 21 and 22 when they are under the influence of the action of the doors.

90 The doors 25 are shown as being connected by hinges to supporting members at the car sides, which members may be side sills. The doors extend inwardly toward the center sills 14, and their inner edges are adapted to bear thereagainst when the doors are closed. When the latter are open, they are adapted to discharge lading below the center sills, as indicated in dot and dash lines in Fig. 3.

When the central chain 19 is wound upon chain spool 7, as shown in Figs. 1 and 2, the inner edges of doors 25 are drawn up against the undersides of the bottom flanges of center sills 14, as is clearly illustrated in Fig. 5. Chains 21 and 22, which are connected to the doors by the eyebolts 24, or other means, and chain 19, to which said chains 21 and 22 are also connected to be moved therewith, may be of comparatively light construction, since said chains are primarily intended to lift and draw the doors 25 to their closed positions after a discharge of lading and when the doors are free from the weight of the lading.

Dependence is not placed upon said chains 19, 21 and 22 to hold the doors tightly closed, and the combined influence of the vibration of the car when in motion and of the weight of the load it carries is liable to tend to permit the doors 25 to sag away from the center sills 14, threatening a shifting through and loss of some kinds of lading. Means is, therefore, provided for locking the doors in place after they have been raised to their closed positions by the door lifting chains 19, 21 and 22.

The door-lifting means and the door-locking means are adapted to be interlocked

with each other through the medium of co-operating shaft 9, and ratchet pawl 12 and locking arm 11 carried thereby, as will hereinafter be made plain.

5 Said door-locking means comprises a plurality of door locking devices having rockable parts and a shaft 26 which extends longitudinally of the car, preferably between the center sills 14 and consequently 10 between the doors.

The door locking devices are best shown in Figs. 2, 3 and 4, and each includes a casting 35, mounted upon the upper flanges of the center sills 14, and is provided with a bearing 36. A rockable crank arm 37 is mounted in said bearing, and pivotally connected therewith and depending therefrom is a link. In Fig. 3, the link is of ordinary form and is designated as 38. In Fig. 4, a link 39 containing a loop 40 therein is substituted for link 38, and link 39 is included in those door locking devices which are so located that the door lifting chains are required to extend through them. Loop 40 in link 39 permits 20 such chain passage in any of its positions, as is indicated in Fig. 4.

The lower ends of links 38 and 39 are pivotally connected to locking dogs 41, rockably mounted on the lower ends of swing 30 links 42, which in turn are pivoted to supporting castings 43 secured to center sills 14 and resting on the bottom flanges thereof and extending below said flanges.

Shaft 26 is mounted in bearings supported 35 from the center sills and is operably connected with the door locking devices, preferably being of rectangular cross section and passing through conforming apertures in the hubs of crank arms 37 of the locking devices. Said shaft 26 at its forward end 40 passes above sheave wheel 15 and terminates shortly behind and somewhat below co-operating shaft 9. On this end of the longitudinally extending shaft 26 is mounted a bifurcated crank arm 27, having a pair of 45 outstanding arms.

These arms are connected at their outer ends by a pin, which also passes through the inner ends of operating rods 28 and 29. The 50 latter extend transversely of the car in opposite directions toward the car sides, which are perforated to allow the outer looped ends of said rods to partly pass therethrough, and the perforations are large enough to enable 55 a trainman's arm to pass freely through them in manipulating said rods 28 and 29.

To the inner faces of the car walls, just below the perforations are secured inwardly 60 extending brackets 30. It has been found convenient to form them as pressings of angular cross section with inner upstanding 65 projections, through each of which passes one of the operating rods 28 or 29, the looped end of which is outside said projection. The

upstanding projections of brackets 30, therefore, constitute stops limiting the inward thrust of said operating rods.

Revolvably mounted on operating rod 28 is a locking clip 31, located in intimate relation with locking arm 11 carried by co-operating shaft 9. Retaining clips 32 are securely clamped to operating rod 28, one on each side of locking clip 31, and each has projections 33, which overlap said locking clip to normally hold it in a position opposing locking arm 11, when shaft 9 is acting to prevent the unwinding of the chains. Figs. 1 and 3 best disclose this condition of the relationship.

And under this condition, the looped end 80 of rod 29, by reason of its proximity to the upstanding projection of its bracket 30, prevents material movement in one direction of either rod 28 or 29. On the other hand, locking arm 11 prevents the movement of 85 these rods in the other direction, by obstructing locking clip 31. Consequently, there can be no unintentional release of the doors.

The interlocking between the door lifting means and the door locking means, previously referred to, is also effective at this time as ratchet pawl 12 engages ratchet wheel 8 on shaft 1, preventing the unwinding of chain spool or drum 7, and, as just described, operating rods 28 and 29 can not 95 be moved to release or unlock the locking devices.

When a release of the doors is desired, one of the operating shaft handles 10, whichever it is most convenient to use, is thrown to revolve 100 co-operating shaft 9, whereupon ratchet pawl 12 is thrown out of engagement with ratchet wheel 8, and at the same time locking arm 11 is rotated out of the path of locking clip 31.

Either operating rod 28 is then pushed in, or operating rod 29 is pulled out, there being a consequent turning of crank arm 27, which rocks shaft 26. The latter, extending through the hubs of the crank arms 37 of the locking devices in operative relation thereto, rocks said crank arms to raise links 38 and 39, which then rock the locking dogs 41 and cause the links 42 supporting them to swing inwardly. Locking dogs 41 are thus withdrawn from under the doors, which drop by gravity to a lading discharging position.

As the doors drop they pull the chains with them, rapidly revolving the spool 7, shaft 1, ratchet wheel 8 and hand wheels 6.

After the discharge, co-operating shaft handles 10 are returned to their former positions, whereupon pawl 12 again engages ratchet wheel 8, preventing retroaction of shaft 1 as it is being turned by hand wheels 6 to rewind the chain upon spool 7, during the door lifting process.

Returning operating rods 28 and 29 to

their initial positions, after the doors have been raised, securely locks said doors in closed position by rocking shaft 26 in a reverse direction. This reverses the action of the parts of the door locking devices and causes locking dogs 41 to extend under doors 25 to press them to their tightly closed positions.

That the parts of the door locking devices 10 may not move excessively in returning to their door locking positions and beyond the locations shown in full lines in the drawings, the crank arms 37, or some of them, are provided with heels or detents 37^a, which 15 may be integral parts of said crank arms 37. When the parts of door locking devices are returned to their door locking positions, detents 37^a engage the top flange of one of the center sills 14 and prevent further movement of said door locking device parts.

Though locking arm 11 is again in its obstructing location before the operating rods 28 and 29 are restored to their original places, the beveled lower face of locking clip 31 enables the latter to ride over locking arm 11, during which action the locking clip swings upwardly about operating rod 28. At the completion of its passage over locking arm 11, locking clip 31 swings by 25 gravity back into its locking arm-opposing position, being prevented from two great a downward movement by projections 33 of retaining clips 32.

The car is then ready to receive a new 35 load, which, when transported to its destination, may be discharged as just described.

The simplicity of the mechanism, its relative cheapness, its light but adequately strong construction, together with the insurance it gives against loss of lading and of safety in operating it, all contribute to make it a valuable addition to the car building art.

I claim:

- 45 1. In combination in a dumping car, a rockable shaft extending longitudinally of said car, door locking means operably connected with and controllable from said shaft, an angularly extending member fixed to said shaft and means operable from the side of said car adapted to actuate said member to rock said shaft.
- 50 2. In combination in a dumping car, a rockable shaft extending longitudinally of said car, door locking devices controllable from said shaft, and means adapted to rock said shaft extending transversely of the car.
- 55 3. In combination in a dumping car, a plurality of doors hinged near the opposite sides of the car, a rockable shaft extending longitudinally of the car between said doors, door locking means operably connected with said shaft and means adapted to rock said shaft from the side of the car to actuate said door locking means.

4. In combination in a dumping car, spaced center sills, side supporting members, doors extending from said side supporting members toward said center sills, rockable door locking means supported near said center sills, a shaft extending longitudinally of 70 said sills and engaging said door locking means and reciprocatory means connected with said shaft adapted to rock the same to actuate said locking means.

5. In combination in a dumping car, center sills, a rockable door lock operable between said sills, center dumping doors adapted to close to positions near said center sills, and means extending longitudinally 80 and transversely of the car adapted to rock said door lock.

6. In combination in a dumping car, doors hinged near the outer sides of the car, spaced center sills, door lifting means and rockable door locking means operable between said center sills and means extending transversely of the car adapted to actuate said lifting and locking means.

7. In combination in a center dumping car having door lifting means movable longitudinally between center sills, spaced center sills, doors hinged near the sides of said cars adapted to dump lading below said sills, door locking means through which the door lifting means is adapted to extend and means adapted to actuate said door locking means.

8. In combination in a center dumping car, opposed oppositely opening dumping doors, a suitable support, a rockable door lock carried thereby and adapted to engage the under sides of said dumping doors and rockable means operable from either side of said car adapted to actuate said door lock to lock or release both doors simultaneously.

9. In combination in a center dump car, dumping doors, spaced center sills, supports carried by said sills, a shaft extending transversely of the car, means connecting said shaft and said doors and supported in part by said supports and rockable door locking means carried by said sills.

10. In combination in a dumping car, center dumping doors, center sills, door locking means carried by said sills, a rockable door-lock-actuating-shaft supported in operative relation to said locking means and means movable transversely of the car adapted to rock said shaft.

11. In combination in a dumping car, center dumping doors, center sills, door locking means carried by said sills, a rockable door-lock-actuating-shaft supported in operative relation to said locking means, 125 means movable transversely of the car adapted to actuate said shaft and a stop adapted to coöperate with said transversely movable means to lock it in a predetermined position.

12. In combination in a dumping car, a center sill, a door adapted to close against the same, door locking means including a rockable member and a stop carried by the latter and adapted to engage said center sill.
13. In combination in a dumping car, spaced center sills, doors adapted to close thereagainst, door locking means comprising a toggle having a lever and a link, means for rocking said lever to actuate said door locking means and a movement-limiting stop on said lever adapted to engage a portion of one of said center sills.
14. In combination in a dumping car having door raising means extending longitudinally of a center sill, a center sill, a door adapted to close against the same, door locking means including an operating toggle having a member provided with a passage through which the door raising means is adapted to pass without interference and means for actuating said operating toggle.
15. In combination in a car door-locking means adapted to co-act with door-raising means, means for engaging doors, an operating toggle therefor comprising a lever and a link the latter having a loop adapted to permit the passage of the door raising means therethrough without interference irrespective of the position of said link.
16. In combination in a dumping car, a rockable shaft extending longitudinally of the car, door locking devices controllable from said shaft, means for rocking the latter comprising a crank attached to said shaft and members connected with the crank and extending toward and operable from the car sides and supports for said members.
17. In combination in a dumping car, a rockable shaft extending longitudinally of the car, door locking devices controllable from said shaft, means for rocking the latter comprising rods connected therewith and extending toward the car sides, supports for said rods and means for preventing actuation of the rods at will comprising a revolute shaft, a locking member thereon, a device on one of said rods adapted to interlock with said locking member and portions on another of said rods and its support adapted to oppose each other.
18. In combination in a dumping car, a rockable shaft extending longitudinally of the car, door locking means controllable from said shaft, operating rods for said shaft extending toward the car sides, supports for said rods, and actuation preventing-and-permitting means for said operating rods comprising a revolute shaft, a locking member thereon, a device on one of said rods adapted to be opposed by said locking member and portions on another of said rods and on its support adapted to oppose each other, rotation of said revolute
- shaft removing said locking member from the path of said rod-carried device and permitting actuation of said operating rods.
19. In a car door locking mechanism, doors adapted to close against car center sills, a single locking toggle having members supported from said sills by oscillatory means, and an operating toggle comprising a link and a lever, an operating shaft to which said lever is attached, said lever having a detent adapted to engage one of said sills to limit movement of said mechanism in one direction.
20. In combination in a car, a shaft extending longitudinally of the car, door locking latches, actuating means therefor operable from the longitudinal shaft, means for rocking said longitudinal shaft, and door lifting means extending through a zone of movement of said actuating means.
21. In combination in a car, door lifting means, a shaft extending longitudinally of the car, door locking latches, actuating means therefor including a member having an axis movable through the path of said door lifting means and being operable from the longitudinal shaft and means extending transversely of the car for rocking said longitudinal shaft.
22. In combination in a car, oppositely opening dumping doors, door closing means, a single door latch-operating shaft extending longitudinally of the car, door locking latches adapted to lock or release said oppositely opening doors, and latch-actuating means operable by said longitudinal shaft and non-interferingly embracing said door closing means.
23. In a dumping car, center sills provided with flanges in their lower portions, doors adapted to close against said flanges, a plurality of door-locking mechanisms for supporting said doors extending between and below said sills, a shaft adapted to simultaneously actuate all of said mechanisms, and castings mounted upon said sills adapted to sustain a longitudinal hopper hood, some of said castings having bearings for said shaft projecting between said sills in proximity to said locking mechanisms therebetween.
24. In a dumping car, center sills provided with flanges in their lower portions, doors adapted to close against said flanges, a plurality of door-locking mechanisms for supporting or releasing said doors, a shaft adapted to simultaneously actuate all of said mechanisms, and castings mounted upon said sills adapted to sustain a longitudinal hopper hood, some of said castings having bearings for said shaft, and some of said castings being recessed to facilitate the operation of said mechanisms.
25. In a car door locking mechanism, doors, car center sills against the bottom of

which said doors are adapted to close, said sills having flanges and webs, supporting castings sustained by said sills and resting upon said flanges, a plurality of oscillatory links pivoted to said castings, locking dogs pivoted to said links and having their inner ends pivoted together, and operating means for said locking dogs.

26. In a car door operating mechanism, 10 car center sills against the bottom of which said doors are adapted to close, said sills having flanges and webs, supporting castings sustained by said sills resting upon said flanges and passing through and below 15 the same, a plurality of oscillatory links pivoted to said castings, locking dogs pivoted intermediate their lengths to said links

and having their inner ends pivoted together, and means for operating said dogs.

27. In combination in a car, a shaft extending longitudinally of the car, oppositely opening doors, door locking latches, actuating means therefor operable by said shaft and including a rockable member provided with a movement-limiting stop and a suitably positioned abutment adapted to be engaged by said stop to limit the movement of said actuating means.

In witness whereof I have hereunto set my hand in the presence of two witnesses.

JOHN M. ROHLFING.
